UNITED STATES PATENT OFFICE.

CHARLES P. STANBON, OF LYNN, MASSACHUSETTS.

STEERING-POST-POSITIONING MEANS.

1,383,348.

Specification of Letters Patent.

Patented July 5, 1921.

Application filed April 6, 1918. Serial No. 227,117.

To all whom it may concern:

Be it known that I, CHARLES P. STANBON, a citizen of the United States, and a resident of Lynn, county of Essex, and State of Massachusetts, have invented an Improvement in Steering-Post-Positioning Means, of which the following description, in connection with the accompanying drawings, is a specification, like characters on the drawings representing like parts.

This invention relates to a novel and improved steering post control for motor vehicles, adapted to neutralize the tendency of obstructions in the road to throw the steering wheel in one direction or the other with the consequent danger of losing control of the car, and adapted also to assist in returning the steering post to normal neutral position after it has been turned from neutral position in the usual operation of the car.

In the drawings illustrating the particular embodiment of my invention described herein,

Figure 1 is a side elevation showing the mechanism as applied to a conventional steering post.

Fig. 2, a side elevation of the mechanism.

Fig. 3, a plan and partly sectional view of the mechanism.

My novel steering post illustrated embodiment of my novel tension and controlling means is designed to exercise a more or less constant pressure upon the steering post to return the same to normal position, and in this way assists the driver in steering the car.

Referring to Figs. 1, 2, it will be seen that the tension means comprises brackets 37, 38, clamped at a convenient point to the steering column or casing 36, by screws 39. The clamping members are extended forwardly and support between them by means of a screw 40 the tension member frame or drum 41. This drum consists of two heads 42, 43, connected by struts 44, and a side wall 45 having opposed openings 46. Within the drum, which is divided by a partition 47, are mounted two tension members, as springs 48, 49, see dotted lines Fig. 3, which are coiled in opposite directions about and secured at their inner ends to the pin 40.

To the outer ends of the springs 48, 49 are connected cords 50, 51, the opposite ends of which are secured in eyes 52, on spring barrels or tension posts 53, carried respectively by rings 54, 55, (Fig. 2) between the

clamps 37, 38 and on the steering post 34. Each barrel 53 carries a tension pin 56 within it, about which is a coiled spring 57, seated at one end against a flange 58 on the pin, and at its opposite end against an adjusting screw plug 59 threaded into the outer end of the barrel 53.

By this means any required adjustment of the spring 57 may be readily obtained. In order that the increased tension may be applied to the post 34 as it is turned by the engagement of the pin 56 therewith, I have conceived the novel construction shown and which is as follows. Each pin 56 is positioned normally at the inner end of a cam shaped slot 60, beginning at the longitudinal center line of the rod at its rear face and gradually increasing in depth toward its front end, the length of the slot being approximately one-quarter of the circumference of the post 34. In this position of the pins (as shown in Fig. 2) each spring exerts its normal and the same tension upon its own side of the post.

As the post 35 is turned in either direction, naturally the tension of the spring engaging the post on that side of the rod is increased in proportion to the extent of the rotation of the post, and this tension tends at all times to return the post 34 to its normal position, the opposite tension member however, exerting less pressure owing to the rotation of its tension post permitting it to wind up, and of course when the steering rod is turned back by the driver to normal position the winding up action of the spring or tension member assists in such operation. Should the steering post be turned more than a quarter turn, thus bringing the forward wheels at approximately right angles to the car, the pin 56 will be, by the cam surface 61, automatically released from the post 34, and the tension thereon released as the post 53 returns freely to normal position.

By the foregoing construction it will be noted that the springs never act in opposition to each other, each acting only when its pin 56 is moved from its normal position and the action is then directed to returning the pin and post to their original positions.

A reasonable amount of tension on these springs will cause them to assist the post 34 at all times to resist any inclination it may have to be turned one way or the other by coming in contact with a stone or other obstruction in the road. The action of the

two springs always tends to retain the forward wheels in longitudinal alinement with the chassis.

It will be obvious that my novel steering post controlling means as described may be modified in many detailed particulars without departing from the spirit of the invention and the scope of the appended claims.

While I have herein described and illustrated one form of my invention, it is not however, limited to the precise construction shown.

Claims:

1. In steering post positioning means a steering column, a steering post, a tension member on the column comprising a frame, resilient members therein, tension posts on the steering post connected with the resilient members, tension pins on said tension posts, tension members for the pins, operative connections between the tension pins and steering post to cause the latter to move the tension posts with increasing tension on the steering post relative to the degree of turning of the latter.
2. In steering post positioning means a steering column, a steering post, tension posts on the latter radially positioned, tension members on the column operatively connected with the tension posts and normally effective in opposite directions, one tension member yielding its effectiveness while the opposite member increases its effectiveness as the steering post is turned.
3. In steering post positioning means a steering column, a steering post, tension posts on the steering post, each having limited movement in one direction and unlimited movement in the opposite direction, tension members on the steering column to move the tension post from its normal position and connected with the steering post, and acting with relatively increasing effect as the steering post is turned to move the tension post away from its tension member, and connections between the steering post and tension posts whereby the latter are automatically freed from connection with the former at a given point in rotation of the steering post.
4. Tension mechanism for a steering post comprising a frame adapted to be mounted on the steering column, resilient members thereon, tension posts connected to the resilient members and adapted to be mounted on the steering post, tension pins on said posts, tension members for the pins, operative connections between the tension pins and steering post to cause the latter to move the tension posts to exert increasing tension on the steering post and tension posts relative to the degree of rotation of the steering post.
5. In steering post positioning means ten-

sion mechanism comprising a frame adapted to be mounted on the steering column, a drum in the frame, resilient members within the drum and secured therein, tension posts on the steering column connected with the resilient members, tension pin receiving means in the steering post, tension pins in the tension posts and received by said receiving means to travel therein and to be actuated thereby during a portion of the movement of the steering post, to increase the action of the resilient members on the tension and steering posts to return the same to normal position, and tension means within the tension posts to retain the pins in normal position.

6. Steering post positioning means comprising brackets adapted to be mounted on the steering column, a frame thereon, oppositely operated resilient members on the frame adapted to be withdrawn therefrom in opposite directions by tension, a steering post within the column, tension posts on the steering column connected with said resilient members to withdraw the same in opposite directions from the frame and to hold the steering post in normal position, tension pin receiving means in the steering post, tension pins in the tension posts and said receiving means, yielding means in the tension posts for retaining the pins in the pin receiving means in normal position, the pins adapted to ride out of the receiving means and upon the post upon rotation of the latter.

7. Steering post positioning means comprising the steering column, a steering post, tension posts on the latter, a frame on the column, tension members on the frame connected each to a tension post, tension pin slots in the steering post having each a cam surfaced bottom, tension pins in the tension posts under pressure and extended into said slots, adapted to ride on said cam surfaces as the steering post is turned and tension cumulatively applied to the steering post as it is turned in opposite directions.

8. In steering post positioning means the column 27 having the frame 41 thereon, coiled tension members 48, 49, in the frame and operative in opposite directions, tension posts 52 on the steering post and connected to the members 48, 49, tension pins 56 in the posts 53, slots 60 in the post 34 receiving the inner ends of the pins 56, springs 57 acting to force inwardly the pins 56, whereby as the post 34 is turned in opposite directions the tension members 48, 49, will alternately act to a cumulative degree to resist said turning movement, and tend to return the post to normal position.

CHARLES P. STANBON.

It is hereby certified that in Letters Patent No. 1,383,348, granted July 5, 1921, upon the application of Charles P. Stanbon, of Lynn, Massachusetts, for an improvement in "Steering-Post-Positioning Means," an error appears in the printed specification requiring correction as follows: Page 2, line 114, claim 8, for the reference numeral "52" read 53; and that the said Letters Patent should be read with this correction therein that the same may conform to the record of the case in the Patent Office.

Signed and sealed this 6th day of September, A. D., 1921.

[SEAL.]

KARL FENNING,

Acting Commissioner of Patents.
